(57) **CLAIM**

We claim the ornamental design for a gas analyzer cover, as shown and described.

DESCRIPTION

FIG. 1 is a right perspective view of a gas analyzer cover according to an embodiment of the new design;

FIG. 2 is a left perspective view thereof;

FIG. 3 is a front view thereof;

FIG. 4 is a rear view thereof;

FIG. 5 is a right-side view thereof;

FIG. 6 is a left-side view thereof;

FIG. 7 is a top view thereof; and,

FIG. 8 is a bottom view thereof.

In these drawings, the solid lines illustrate the claimed ornamental design, whereas the broken lines illustrate unclaimed subject matter and form no part of the claimed design. The dashed broken lines in FIGS. 1-3 represent a screen that may be included within the cover, and form no part of the claimed design.
